CABINET FOR A HEATER OR THE LIKE

Harold D. Fetty, Detroit, Mich., assignor to Motor Wheel Corporation, Lansing, Mich., a corporation of Michigan

Application June 14, 1957, Serial No. 46,599

Term of patent 7 years

(Cl. D81—19)

Fig. 1

Fig. 1 is a front perspective view of a cabinet for a heater or the like, showing my new design.

Fig. 2 is a top view of the cabinet.

Fig. 3 is an end view of the cabinet.

Fig. 4 is a fragmentary sectional view along the line 4-4 of Fig. 2.

The back of the cabinet is plain.

The dominant features of the design reside in the portions shown in full lines.

I claim:

The ornamental design for a cabinet for a heater or the like, substantially as shown and described.
